HALFDAN A. STEEN, OF MILWAUKEE, WISCONSIN, ASSIGNOR TO THE CUTLER-HAMMER MFG. CO., OF MILWAUKEE, WISCONSIN, A CORPORATION OF WISCONSIN.

LIQUID RHEOSTAT.

1,161,993.

Specification of Letters Patent.

Patented Nov. 30, 1915.

Application filed October 23, 1914. Serial No. 868,217.

To all whom it may concern:

Be it known that I, HALFDAN A. STEEN, a subject of the King of Norway, residing at Milwaukee, in the county of Milwaukee and 5 State of Wisconsin, have invented new and useful Improvements in Liquid Rheostats, of which the following is a full, clear, concise, and exact description, reference being had to the accompanying drawing, forming a part of this specification.

This invention relates to liquid rheostats. Such rheostats are frequently employed for accelerating and regulating electric motors where, to meet different load conditions, they 15 must be adjusted for widely different resistance values. Heretofore such adjustments have been effected either by varying the level of the rheostat fluid or by adjusting the rheostat electrodes.

20 This invention has among its objects to provide means for more readily and expeditiously accomplishing the aforesaid results.

A further object is to provide means for the aforesaid purpose which eliminates the 25 necessity for varying either the fluid level or the position of the electrodes to effect wide resistance adjustment and which increases the fineness of subsequent regulation obtainable by such relative liquid level variations.

30 Further objects and advantages will appear hereinafter in connection with the following description of a typical embodiment of the invention schematically illustrated in the accompanying drawing.

35 Referring more specifically to the drawing, there is shown a conventional form of tank having an upper compartment 1, for the electrodes and a lower compartment 2 constituting a reservoir for the water or 40 other liquid which is fed into the compartment 1 as required, by a pump 3. The compartment 1 has an outlet 4 communicating with the compartment 2 and provided with adjustable means 5 for regulating the size 45 thereof to thereby regulate the level of the liquid circulating in said compartment 1. Also said outlet is so positioned as to retain in the compartment 1 at all times a predetermined amount of liquid.

Considering now the electrodes 6 illustrated, the same are adapted to be supported at the desired height in the compartment 1 in the usual manner but they are unlike the usual electrodes in important respects. Whereas the ordinary electrodes are electri-

cally unitary those illustrated are each divided into a plurality of electrically independent sections and are provided with controlling means hereinafter described whereby the circuit connections to said sections 60 may be readily varied to vary the current carrying area of the individual electrodes and thereby adjust the resistance value of the rheostat for a given level of liquid.

More specifically, the electrodes illustrated 65 are each divided into two sections *a* and *b* of different surface areas and said sections are arranged to be included in circuit selectively by a suitable switch 7 or in parallel by said switch 7 and a suitable auxiliary 70 switch 8. Thus the effective area of each electrode and consequently the total resistance of the rheostat for a given liquid level may be varied to three values, *i. e.*, full effective area with a consequent minimization 75 of resistance by paralleling the sections *a* and *b*, minimum effective area with a consequent maximization of resistance by inclusion of only the smaller section *b* and mean effective area and resistance by inclusion of 80 only the larger section *a*.

Of course it will be understood that the 85 number and relative sizes of the electrode sections may be varied as desired and that such sections may in practice be of any preferred shape and size and mechanically connected to provide a unitary electrode. Hence it will be apparent that the rheostat may be readily designed to meet varying 90 load conditions and readily adjusted by 95 mere variation of connections to meet the widely different conditions as they arise without resorting to the time consuming and in other respects unsatisfactory method of adjusting the electrodes in the liquid or 100 varying the liquid level with respect to the electrodes. At the same time, the adjustment provided by the sectional electrodes also increases the range of subsequent adjustment attainable by variation of the liquid level, since, as will be apparent, such 105 variation may be effected by raising or lowering the liquid level from maximum to minimum under each condition of circuit connection of the electrodes. Moreover, the 110 fineness of such regulation is augmented since slight adjustments may generally be obtained by variations in the relative liquid level while a relatively large area of the electrodes is immersed so that comparatively

wide variations in the liquid level effect only comparatively small resistance changes.

What I claim as new and desire to secure by Letters Patent is:—

- 5 1. In a liquid rheostat, electrode plates divided into sections and means for connecting such sections in circuit selectively.
- 10 2. In a liquid rheostat, electrode plates divided into sections of different current carrying area and means for connecting such sections in circuit selectively.
- 15 3. In a liquid rheostat, electrode plates divided into sections and means for selectively including in circuit one or more of such sections.
- 20 4. In a liquid rheostat, electrode plates divided into sections and means for selectively including in circuit all or any one of such sections.
- 25 5. In a liquid rheostat, electrode plates divided into sections, and means for paralleling such sections and also means for excluding certain of the same from circuit.
- 30 6. In a liquid rheostat, electrode plates divided into sections, and means for paralleling such sections and also means for excluding any of the same from circuit selectively.
- 35 7. In a liquid rheostat, electrodes divided into sections of different current carrying area and means for including in circuit a variable number of such sections.
8. In a liquid rheostat, electrodes divided into sections of different current carrying area and means for including in circuit all of such sections or any of the same selectively.

9. In a liquid rheostat, electrodes of different capacities arranged in groups and means for paralleling the electrodes of each group and also means for connecting in circuit certain of the same to the exclusion of the remainder.

10. In a liquid rheostat, electrodes of different current capacities arranged in groups and means for paralleling the electrodes of each group and also means for connecting in circuit any one of the same to the exclusion of the remainder.

11. In a liquid rheostat, in combination, a container, liquid resistor therein, a plurality of electrodes immersed in said resistor, means for varying the level of said resistor relative to said electrodes for varying the resistance value of the rheostat, and means for varying the effective immersed area of said electrodes to vary the amount of resistance difference effected by a given variation in the resistor level.

12. In a water rheostat, in combination, a plurality of electrodes of different surface areas and means to vary the circuit connections therebetween for effecting any given resistance adjustment with a minimum change of water level and with a minimum length of water line on the current carrying electrodes.

In witness whereof, I have hereunto subscribed my name in the presence of two witnesses.

HALFDAN A. STEEN.
